UNITED STATES PATENT OFFICE.

ARAM HOGASSIAN, OF NEW YORK, N. Y.

BELT BUCKLE.

Application filed April 24, 1924. Serial No. 708,794.

To all whom it may concern:

Be it known that I, ARAM HOGASSIAN, a citizen of Armenia, residing at city of New York, State of New York, have invented 60
5 certain new and useful Improvements in Belt Buckles, of which the following is a specification.

This invention relates to improvements in belt buckles and more particularly to that 65
10 type which are placed upon the market and sold independently of the belt.

There are various designs of buckles of 70
15 this type which embody means for frictionally gripping the free end portion of the belt after the belt has been tightened, and ordinarily the gripping element is arranged to engage the outer or finished surface of the belt.

The tendency of the belt to slip, when 75
20 equipped with such a buckle, results in mutilation of the belt to a greater or less extent, thereby rendering it unsightly. Furthermore, there is, in such buckles, an absence of any positive locking means to prevent 80
25 displacement of the parts of the buckle and permit slipping of the belt. Therefore, it is one of the important objects of the present invention to provide a belt buckle which will overcome these disadvantages and obviate 85
30 any mutilation of the belt and effectually prevent slipping of the belt, after it has been adjusted.

Another disadvantage presented by belt buckles of the type referred to above is that 90
35 they themselves do not conform snugly to the contour of the body when applied and adjusted and in the majority of instances, they so distort the belt that it likewise, at the portion of its length which is adjacent to 95
40 the buckle, does not conform snugly to the contour of the body. Therefore, it is another important object of the invention to provide a buckle so constructed as to obviate 100
45 these disadvantages, thus rendering the buckle and the belt to which it is applied more attractive and neater in appearance than belts equipped with buckles presenting the disadvantages outlined.

The buckle of the present invention embodies, as usual, a face plate and means carried thereby for coaction with the free end portion of the belt for holding the belt in place after it has been adjusted about the body and another important object of the 105
55 invention is to so construct the holding means that it will firmly and snugly hold

the belt against the rear face of the face plate so that the belt will lie perfectly flat or snug against this face and, therefore, not be distorted as is ordinarily the case. 110

Another important object of the invention is to provide means for automatically locking the holding means referred to above, at the time and after the belt has been tightened or adjusted, so that there will be no tendency toward or likelihood of the holding means becoming displaced with relation to the face plate at such time as body movement might temporarily contract the abdomen and momentarily leave the belt more or less slack. 115

In the accompanying drawings:

Figure 1 is a perspective view of one form of buckle embodying the invention, the view illustrating also the belt to which the buckle 120
75 is connected.

Figure 2 is a rear elevation of the buckle and the adjacent portion of the belt.

Figure 3 is a horizontal sectional view taken substantially on the line 3—3 of Figure 2, looking in the direction of the arrows, the buckle being closed. 125

Figure 4 is a perspective view of the buckle looking at the rear side thereof, the belt holding member of the buckle being shown as swung to open position. 130

Figure 5 is a detail vertical front to rear sectional view taken substantially on the line 5—5 of Figure 4, looking in the direction of the arrows. 135

Figure 6 is a view similar to Figure 1, illustrating another embodiment of the invention.

Figure 7 is a view similar to Figure 2, illustrating the modification shown in Figure 6. 140

Figure 8 is a horizontal sectional view taken substantially on the line 8—8 of Figure 7.

Figure 9 is a perspective view of the buckle, the belt holding means being shown swung to open position. 145

Figure 10 is a vertical sectional view taken substantially on the line 10—10 of Figure 9, looking in the direction of the arrows. 150

Referring first to that embodiment of the invention illustrated in Figures 1 to 5 inclusive, the buckle comprises a face plate which is indicated in general by the numeral 1 and which may have its outer face embossed or otherwise ornamented in any de- 155

sired manner as is customary in articles of this class. Preferably, this face plate is both longitudinally and vertically curved, as will be evident by a comparison of Figures 3 and 5 of the drawings, the curvature being relatively slight but, at the same time, of sufficient degree to insure of a secure locking of the belt in a manner which will presently be explained. At its upper and lower edges, the face plate 1 is provided with rearwardly projecting flanges which are indicated by the numeral 2, these flanges extending longitudinally of the respective edges of the face plate preferably for a considerable portion of the said edges. For a purpose to be presently explained, the flanges 2 each have one end portion deflected inwardly to a slight degree, as indicated by the numeral 3 and as clearly shown in Figure 5 of the drawings, and, by stamping or otherwise, the deflected end portion 3 of each flange is provided with a relatively short longitudinally extending inwardly presented rib 4 adjacent its longitudinal free edge.

The bail of the buckle is indicated in general by the numeral 5, and the said bail is in the general form of a hollow rectangle and includes upper and lower sides 6, a bar 7 connecting the inner ends of the said sides, and a bar 8 connecting the outer ends of the sides, the former bar having its ends projecting beyond the said side members 6 so as to provide short tongues which fit pivotally in openings formed in the flanges 2. The side members 6 of the bail are preferably flat-sided and their longitudinal edges 10, which are to be presented toward the rear face of the face plate 1, in the closed position of the bail, may be curved to conform substantially to the longitudinal curvature of the said face plate 1, their opposite longitudinal edges being, however, preferably straight. For a purpose to be presently explained, the bar 7 is longitudinally curved and its curvature conforms substantially to the vertical curvature of the face plate 1. This bar 7 is likewise provided with a tongue 11 which is slightly longitudinally curved and extends from the said bar in the general direction of the bar 8, the extremity of the tongue being transversely rounded, as indicated by the numeral 12. The curvature of the tongue 11 is on such a line that when the bail is swung to position lying against the rear face of the face plate 1, the extremity of the tongue will be presented directly toward the said face of the face plate. A loop 13 is provided at the outer end of the bail and is integrally connected at its ends to the outer corners of the bail frame. This loop constitutes a means whereby the buckle may be permanently connected with one end of the belt, which belt is indicated in the drawings

by the numeral 14, and the said belt is looped at its said end through the said loop and said end is secured preferably by snap fasteners indicated by the numeral 15, as is customary in articles of this class.

When it is desired to apply the belt about the body, the bail 5 is swung substantially to the position shown in Figure 4 of the drawings, and the free end portion of the belt, which is provided with the usual openings 16, is inserted through the bail frame, and the belt tightened, that end of the face plate 1 toward which the tongue 11 then projects, being swung slightly outwardly from the body so that the said free end portion of the belt will ride over the tongue until, when the belt has been tightened, one of the openings 16 therein will be in position to receive the said tongue. At this time, the said end of the face plate 1 is released, and due to the tensioned state of the belt 14, the bail 5 will be held securely in a position lying very close to the rear face of the face plate 1 and, in fact, with the edges 10 of its side members substantially in contact with the said rear face of the face plate. The curvature of the tongue 11 is such that not only will the tongue engage through the said opening 16 in the belt, as clearly shown in Figure 3 of the drawings, but, furthermore, the tongue will be caused to bear firmly against the inner side of the adjacent portion of the belt, as shown in said figure, so as to snugly bind this portion of the belt and the adjacent portions against the inner face of the said face plate. It will be evident that, due to the longitudinal and vertical curvature of the face plate and the corresponding curvature of the bar 7 of the bail, the portion of the belt which is engaged through the buckle will be correspondingly curved to thus render the article smooth and neat in appearance. As the bail 5 assumes its locking position, the side members 6 of the bail frame will move past the deflected end portions of the flanges 2 and past the ribs 4 upon these end portions of the flanges and, due to the resiliency of the flanges 2, the straight edges of the said side members 6 will snap behind the ribs and the bail will thus be securely locked against displacement with relation to the face plate 1 of the buckle.

The form of the invention just described is adapted for application both to men's and ladies' belts and is especially well adapted for the latter use inasmuch as ladies' belts are sometimes worn more or less loosely and yet, notwithstanding this fact, there is no likelihood of the belt slipping or any displacement of the holding member of the buckle with relation to the face plate thereof such as would release the belt.

Referring now to the embodiment of the invention illustrated in Figures 6 to 10 in

clusive, the buckle is indicated in general by the numeral 17 and the same comprise a face plate 18 which corresponds in contour substantially to the face plate of the previously described form of buckle. Flanges 19 are formed at the upper and lower edges of the face plate 18 and project rearwardly from the said plate and each flange has a deflected end portion indicated 10 by the numeral 20 and corresponding to the deflected end portions of the flanges previously described. Likewise, as in the previously described form, the deflected portion 20 of each of the flanges 19 is provided with a rib 21. In this embodiment, each flange is provided at its rear edge with a belt guiding lip 22 projecting substantially at right angles from the plane of the flange 19 and in an inward direction so that 20 the lips are presented toward each other in spaced relation.

The numeral 23 indicates in general the bail of the buckle and this bail is of approximately rectangular form and substantially flat-sided. At one side, the metal of which the bail 23 is formed, is bent upon itself to provide a sleeve 24, and a pivot pin 25 engages through this sleeve and is anchored at its ends in the flanges 19 at points substantially midway between the ends of the said flanges, the bail being in this manner swingingly connected with the face plate 18. The bail 23 has straight upper and lower edges which are designed to ride past the deflected end portions 20 and the ribs 21 of the flanges 19 as the bail is swung to locking or gripping position, and the bail is thus locked in the same manner as the bail of the previously described form of the invention.

This embodiment of the invention is of the friction type and the invention contemplates a novel arrangement of friction gripping elements upon the bail 23 to insure of a positive gripping of the free end portion of the belt when inserted through the buckle and adjusted. One of these elements is in the nature of a gripping tongue 26 which may constitute a continuation of one side of the bend forming the sleeve 24, or may constitute a separate element integrally united to the said side of the bend. In any event, the said tongue is provided with a gripping edge 27 which is curved on an arc corresponding to the arc of curvature of the face plate 18 from top to bottom, and the tongue is located at that side of the bail 23 which is presented toward the face plate, when the bail is in gripping position. Another one of the gripping elements referred to above is in the form of a tongue 28 stamped out from the plate comprising the bail 23 and curved in a direction to have its free end presented toward the rear face of the face plate 18 when the bail is in gripping position, this

end of the said tongue being rounded as indicated by the numeral 29, so as not to injure the belt. The third element is indicated by the numeral 30 and constitutes that portion of the bail which is located immediately beyond the tongue 28 in the direction of the free end of the bail, this gripping element being a relatively narrow portion of the plate from which the bail is formed and being deflected or bent from the plane of the bail plate, as indicated by the numeral 31, so as to provide a rounded or curved bearing surface to engage with the inner side of the belt, as clearly shown in Figure 8 of the drawings. The bail is provided at its free end with a loop 32 corresponding to the loop at the free end of the bail of the previously described form of buckle, and one end of the belt, indicated by the numeral 33, is looped through this loop and secured by the usual snap fasteners 34. In applying the belt with the present form of buckle, the bail 23 is swung outwardly approximately to the position shown in Figure 9, and the free end portion of the belt is inserted behind the guide lips 22 and between the rear face of the face plate 18 and the pivot for the bail, the belt being then drawn about the body until the desired adjustment is obtained, and then being released. The tendency of the free end portion of the belt to slip through the buckle and the engagement of the edge 27 of the tongue 26 with the inner side of the belt results in the bail 100 being drawn closely to the rear face of the face plate 18 so that this edge of the tongue will firmly bite into the belt as will also the rounded end 29 of the tongue 28. Likewise, the rounded bearing or gripping portion 30 of the bail will be caused to bear firmly against the inner side of the belt and due to the corresponding curvature of this part and the face plate 18 and likewise the corresponding curvature of the edge 27 of the tongue 26 and the said face plate 18, the belt will be firmly held in place between the gripping elements and the face plate and slippage of the belt will be positively prevented.

From the foregoing description of the invention, it will be evident that in both forms thereof, the buckle may be readily and conveniently applied to a belt designed for use in connection with buckles of this general type and, when applied, will permit of convenient adjustment of the belt about the body and insure against loss of the original adjustment through slippage of the belt or a displacement of the parts of the buckle as frequently occurs in the use of previously designed buckles of this class.

The form of buckle last described is designed especially for adaptation to men's belts inasmuch as such belts are ordinarily 130

more or less tightly drawn about the body.

Having thus described the invention, what I claim is:

1. A belt buckle comprising a face plate, a bail swingingly mounted thereon, means upon the bail for the connection thereto of one end of a belt of ordinary type provided with openings, and a tongue upon the bail for engagement in the said openings in the belt, the said bail having an open portion through which the belt end is insertible and the said tongue projecting into said open portion of the bail.

2. A belt buckle comprising a face plate, a bail swingingly mounted thereon, means upon the bail for the connection thereto of one end of a belt of ordinary type provided with openings, and a tongue upon the bail for engagement in the said openings in the belt, the said bail having an open portion through which the belt end is insertible and the said tongue projecting into said open portion of the bail and being curved in a direction to present its free end toward the rear face of the face plate when the bail is in holding position.

3. A belt buckle comprising a face plate, a bail swingingly mounted thereon, and of open rectangular form, one side of the bail having projecting end portions pivotally connected with portions of the face plate to provide for such swinging movement of the bail, means at the opposite side of the said bail for the connection thereto of one end of the belt, and a tongue upon the first mentioned side of the bail projecting therefrom in an inward direction toward the last mentioned side of the bail and curved for engagement through openings in the said belt and in a direction to have its extremity

presented toward the rear face of the face plate when the bail is in holding position.

4. A belt buckle comprising a face plate, a bail swingingly mounted thereon and of open rectangular form, one side of the bail having projecting end portions pivotally connected with portions of the face plate to provide for such swinging movement of the bail, means at the opposite side of the said bail for the connection thereto of one end of the belt, and a tongue upon the first mentioned side of the bail projecting therefrom in an inward direction toward the last mentioned side of the bail and curved for engagement through openings in the said belt and in a direction to have its extremity presented toward the rear face of the face plate when the bail is in holding position, said face plate being longitudinally and perpendicularly curved, and the first mentioned side of the bail being curved to conform substantially to the perpendicular curvature of the said face plate.

5. A belt buckle comprising a face plate, flanges at the upper and lower edges of the plate, the said flanges each having one end deflected toward the other flange, a bail swingingly mounted upon the face plate between the said flanges and having side members for frictional engagement behind the deflected end portions of the said flanges in the holding position of the bail, and means upon the bail for holding engagement with the belt, the said deflected end portions of the flanges having ribs upon their opposing faces for coaction with the said members of the bail to lock the same in holding position.

In testimony whereof I affix my signature.

ARAM HOGASSIAN [L. S.]
